United States Patent Office

Des. 210,891
Patented Apr. 30, 1968

210,891

GAME BOARD

Charles F. Foley, Minneapolis, and Charles D. McCarthy,
Deephaven, Minn., assignors to Milton Bradley Com-
pany, Springfield, Mass., a corporation of Massachusetts

Filed Sept. 15, 1967, Ser. No. 8,610

Term of patent 14 years

(Cl. D34—5)

FIG. 1

FIG. 2

FIGURE 1 is a plan view of our game board embodying our new design; and

FIGURE 2 is a side elevational view thereof, the back being substantially plain.

We claim:

The ornamental design for a game board, as shown and described.
